(57) **CLAIM**

The ornamental design for an adjustable bed, as shown and described.

DESCRIPTION

FIG. 1 is a perspective view of an adjustable bed in accordance with the present invention;

FIG. 2 is a top view of the adjustable bed of FIG. 1;

FIG. 3 is a side view of the adjustable bed of FIGS. 1 and 2, the opposite side being a mirror image thereof;

FIG. 4 is a bottom view of the adjustable bed of FIGS. 1-3; and,

FIG. 5 is a front view of the adjustable bed of FIGS. 1-4. The broken lines shown in the Figures are for environmental purposes only and form no part of the claimed design.
